CLAIM

The ornamental design for a bullet casing bracelet, as shown and described.

DESCRIPTION

FIG. 1 is a perspective view of a bullet casing bracelet, showing my new design;

FIG. 2 is a side view thereof;

FIG. 3 is a front view thereof;

FIG. 4 is a back view thereof; and,

FIG. 5 is a top view thereof.

The broken lines in the drawings illustrate portions of the bullet casing bracelet that form no part of the claimed design.
